UNITED STATES PATENT OFFICE.

MALCOLM NEIL LENNING, OF ESK BANK, SASKATCHEWAN, CANADA.

CLOTHES-SPRINKLER.

1,100,314.

Specification of Letters Patent. Patented June 16, 1914.

Application filed January 19, 1914. Serial No. 813,073.

To all whom it may concern:

Be it known that I, MALCOLM N. LENNING, a subject of the King of England, residing at Esk Bank, in the Province of Saskatchewan, Dominion of Canada, have invented certain new and useful Improvements in Clothes-Sprinklers, of which the following is a specification, reference being had to the accompanying drawings.

10 This invention relates to new and useful improvements in sprinkling devices and more particularly to a clothes sprinkler and the primary object of the invention is to provide a device of this character which may be 15 readily and quickly operated to sprinkle the garments in laundry use, whereby to make the application of the water entirely sanitary.

20 A further object of the invention resides in providing a sprinkler which is simple and durable in construction, inexpensive to manufacture and one which will be very efficient and useful in operation.

25 With these and other objects in view, the invention consists in the novel features of construction, combination and arrangement of parts as will be hereinafter referred to and more particularly pointed out in the specification and claims.

30 In the accompanying drawing forming a part of this application, Figure 1 is a section through a device constructed in accordance with my invention. Fig. 2 is an elevation thereof with parts broken away. Fig. 3 is 35 an enlarged detail section through the same; and Fig. 4 is a horizontal section through the device.

40 In describing my invention, I shall refer to the drawing in which similar reference characters designate corresponding parts throughout the several views, and in which 1 indicates a receptacle of any desired size, having a bottom 2 formed thereon, which is provided with a plurality of openings 3 45 and also mounted in the receptacle in slightly spaced relation above the bottom 2, is an auxiliary bottom 4 which is also provided with perforations 5, alining with the openings 3 in the bottom 2. The openings 50 in said bottoms 2 and 4 are arranged in series, the series being spaced by a blank portion in said bottoms. A top 6 is also provided for the receptacle which may be 55 of any preferred type and a handle member 7 is provided on the body portion of the receptacle.

Slidably arranged in the space between the bottoms 2 and 4, is a disk-like sliding member 8 which is formed of sections of semi-circular design and connected together 60 by the arms or sections 9. These semi-circular sections of the member 8 are also provided with perforations 10 which, in one position of the member 8 are adapted to register with the alining openings 3 and 5 65 in the bottoms 2 and 4. I have provided an improved means for the actuation of this sliding member 8, whereby said openings may register or be disposed out of registration, as desired. To this end, an arm or 70 lever 11 is fulcrumed at a point 12 on the upper portion of the handle member 7, the outer end of this lever or arm being designed to form a finger-piece indicated as 13. The opposite end portion of the lever or arm 75 11 is disposed through a slot in the wall of the member 1 and has pivoted thereto a depending rod 14. The lower end of this rod has pivotal connection with one arm of a bell crank lever 15, the latter being fulcrumed as at 16 at a point adjacent the bottom of the receptacle 1. The opposite arm of the bell crank lever is pivoted to an extension 17 formed on the sliding member. In order to entirely inclose the operating 80 parts for the sliding member, an inclosing wall or the like 18 is provided, which extends substantially the full length of the receptacle. This inclosing wall 18 entirely 85 incloses the depending rod 14 and its operating parts. A coil spring 19 is provided at a point between the finger-piece 13 on the lever or arm 11 and the handle member 7 which has a normal tendency to force upwardly on said finger-piece. Under such 90 action, the sliding member 8 is in a position to dispose the openings 10 thereof out of registration with the openings in the bottoms 2 and 4, thus preventing the contents of the receptacle 1 from being expelled 95 100 therefrom.

105 This device is particularly adapted for use in connection with laundries, wherein it is desired to sprinkle the clothes with water prior to the ironing thereof. When it is desired to sprinkle the garments, assuming that the receptacle is already filled with water, it is only necessary to grasp the device by the handle member 7 and holding it over the garments, press downwardly upon the finger-piece 13. This operation, which compresses the coil spring 19, obviously 110

moves the sliding member 8 to a position where the perforations therein register with the perforations in the bottoms 2 and 4. The contents of the receptacle 1 may, therefore, be sprinkled upon the garments and as soon as pressure is released from the finger-piece 13, said sliding member will be returned to its initial position and prevent further sprinkling of the water.

10 From the foregoing it will be seen that I have provided a device which is simple and durable in construction, inexpensive to manufacture and one which will be very efficient and useful in operation and while 15 I have particularly described the elements best adapted to perform the functions set forth, it is obvious that various changes in form, proportion and in the minor details of construction may be resorted to without 20 departing from the spirit or sacrificing any of the principles of the invention.

Having thus described this invention, what I claim is:

1. A device of the class described comprising a receptacle having a perforated bottom, a perforated sliding member mounted on said bottom, the openings of which are adapted to register with the openings in said bottom in one position of said member, 25 a handle member carried on said receptacle, a lever fulcrumed on the receptacle and having a finger-piece arranged adjacent the handle member, means in connection with said lever and said sliding member to actually 30 move the latter upon the actuation of the former, and yielding means between the handle member and said lever, whereby to normally maintain said sliding member in a position so that the openings thereof are 35 out of registration with the openings in said bottom.

2. A receptacle of the class described comprising a perforated bottom, a perforated

sliding member mounted on said bottom, the openings of which are adapted to register 45 with the openings in said bottom in one position of said member, a handle member on said receptacle, a lever fulcrumed on said receptacle and having one end thereof arranged adjacent the handle member, the opposite end thereof being disposed within the receptacle, connecting means between the last mentioned end of said lever and said sliding member to actuate the latter upon the actuation of the lever, spring means in 50 connection with said handle member and said lever to normally maintain the sliding member in a predetermined position, and means arranged in said receptacle to conceal the operating parts thereof.

3. A device of the class described comprising a receptacle having a perforated bottom, a false bottom mounted above the aforesaid bottom and also perforated, the openings therein alining with the openings 65 in the first mentioned bottom, a perforated sliding member arranged between said bottoms, the openings in said member being adapted to register with the openings in 70 said bottoms in one position of the sliding member, a handle member carried on said receptacle, a lever fulcrumed on the receptacle adjacent said handle, connecting means between one end of said lever and said sliding member to actuate the latter upon the 75 actuation of said lever, and spring means engaging with said handle and lever to normally maintain the latter and the sliding member in a predetermined position.

In testimony whereof I hereunto affix my 80 signature in the presence of two witnesses.

MALCOLM NEIL LENNING.
